SHOE SOLE

Alvin L. Diller, Watertown, Mass., assignor to The
B. F. Goodrich Company, New York, N. Y., a
corporation of New York

Application November 26, 1949, Serial No. 6,276

Term of patent 14 years

(Cl. D7—5)

To all whom it may concern:

Be it known that I, Alvin L. Diller, a citizen of the United States of America residing at Watertown, in the county of Middlesex and Commonwealth of Massachusetts, have invented a new, original, and ornamental Design for a Shoe Sole, of which the following is a specification, reference being had to the accompanying drawing, forming a part thereof.

In the drawing:

Fig. 1 is a plan view of a shoe sole embodying my design; and

Fig. 2 is a longitudinal sectional view along the line 2—2 of Fig. 1.

I claim:

The ornamental design for a shoe sole, as shown.

ALVIN L. DILLER.
